UNITED STATES PATENT OFFICE.

MARTIN ZAWISTOWSKI, OF BROOKLYN, NEW YORK.

FUR-CUTTING MACHINE.

1,341,450.

Specification of Letters Patent. Patented May 25, 1920.

Application filed July 27, 1918. Serial No. 246,957.

To all whom it may concern:

Be it known that I, MARTIN ZAWISTOWSKI, a citizen of the United States, and a resident of Brooklyn, in the county of Kings and State of New York, have invented certain new and useful Improvements in Fur-Cutting Machines, of which the following is a specification.

In the making of garments and other articles of pieces of fur cut to the desired shape and sewed together, it is common practice, with certain kinds of fur, to form serrations or notches of approximately uniform size and spacing along the edges of the piece and fit and sew the serrations of abutting edges together so that the seam is a zigzag one and less noticeable beneath the hair.

My invention is a machine for producing such serrations or notches and although certain features of the machine particularly adapt it for cutting fur or long nap material, it may be used on any fabric, paper, or other sheet material. Important objects of my invention are to avoid the necessity of marking each cut on the material and cutting by hand to the line as is common practice; to avoid the necessity of clamping the material in place before cutting; and to permit a straight or curved edge of any length to be serrated as the material is fed through the machine.

One of the important features of my invention is a reciprocating knife so mounted and driven that after each cutting stroke it is turned and makes the next succeeding cut at the desired angle, for instance 90° to the last preceding cut, as the material is fed through the machine in a direction substantially at right angles to the bisector of the angle between two adjacent cuts. A further important feature of my invention involves means for intermittently feeding the material through the machine step by step, the feeding movements being timed in respect to the operation of the reciprocating and oscillating cutter so that a continuous zigzag cut is produced. As a further important feature of my invention I provide a wheel having on its periphery a zigzag slot corresponding to the serrations to be cut in the fur or other material, the periphery of the wheel serving as a support against which the material is pressed during the stroke of the cutter, to advance the material

by the rotation of the wheel between successive cutting strokes, and to permit the movement of the hair away from the hide during the cutting of the latter so that the hair, normally projecting across the path of the knife, is not cut or injured.

In the accompanying drawings I have illustrated one embodiment of my invention but as various changes in the details of construction and the arrangement of parts may be made within the scope of my invention as defined in the appended claims, I desire this form to be considered in an illustrative rather than in a limiting sense. The mechanical equivalents may be substituted for various specific features illustrated without effecting the efficiency of the machine or its principles of operation.

In the accompanying drawings:

Figure 1 is a perspective view of a machine embodying my invention, most of the supporting parts or the operating mechanism being shown in section on the vertical longitudinal center line of the machine.

Fig. 2 is a central longitudinal section.

Figs. 3, 4, and 5 are sectional details on the lines, 3—3, 4—4, and 5—5 respectively of Fig. 2.

Fig. 6 is a sectional detail of the feeding and material supporting wheel.

Fig. 7 is a view of a form of knife which may be employed, and

Fig. 8 is a fragmentary edge view of the wheel.

I have illustrated the working parts of my improved machine supported in a frame somewhat similar to that of an ordinary sewing machine. On the table or platform 10 is supported a hollow upright or standard 11 from which projects a hollow arm 12 carrying a head 12a. These may be formed integral of cast metal if desired. A substantially horizontal main drive shaft 13 is journaled in the arm 12 and has on its outer end a drive pulley 14 receiving power through a belt 15 from an electric motor, a foot treadle, or any other source of power. Beneath the platform or table 10 is a second shaft 16 geared to the shaft 13 and rotated at a definite predetermined relative speed and maintained at all times in proper step. In the specific form illustrated, the shaft 13 is driven at twice the speed of the shaft 16. The power transmitting mechanism extends

through the standard or upright 11 and may be of any suitable character, as for instance, gears, sprockets and chain, or other means which will prevent slippage or any material lost motion. As shown, the two shafts have sprocket wheels 17 and 18 over which extends a belt 19. It is evident that the pulley 14 may be on the shaft 16 instead of on the shaft 13. Mounted for reciprocation within the head 12^a is a vertically disposed cutter bar 20, having at its lower end a knife or cutter 21, for instance, of the form shown in Fig. 7. This cutter has a vertical edge in the axis of the reciprocatory cutter bar 20 and has a lower beveled cutting edge. Any suitable means may be provided for effecting the reciprocation of the bar 20 upon the rotation of the shaft 13. Merely as an example of such a mechanism, I have illustrated the shaft 13 provided with a disk 22. Pivotally mounted on the face thereof so as to swing in a plane parallel to the face of the disk is a link 23, the point of attachment of the link to the disk being eccentric in respect to the axis 13. The opposite end of the link is pivoted to a yoke 24 secured to the bar 20 so that during the rotation of the shaft and its disk, the bar is reciprocated. The desired range of movement of the cutter bar may be varied by varying the eccentricity of the point of attachment of the link to the disk.

To cut the successive sides of the notches or serrations, I provide means for oscillating the cutter about its axis through an angle corresponding to the angle between the sides of the serrations. I have illustrated such angle as approximately 90°. Various means may be employed for effecting this intermittent oscillation each time the cutter is in raised position and holding it against oscillation while the cutter is at the lower end of its stroke or in the work. Merely as an example of such means, I have illustrated a slide including a frame 25 encircling the shaft 16, supporting pins 26 mounted to slide in bearings 27 depending from the table, and an upwardly extending rod 28. The frame 25, supporting pins 26, and rod 28 are rigid in respect to each other and might be made integral. Within the frame 25 the shaft 16 has a cam 29 of such form that the slide is moved intermittently first in one direction and then in the other and is held stationary for a considerable period of time after each movement. As the shaft 16 is rotated at only one half the speed of the shaft 13 this cam is so designed and so timed that it gives the slide a movement in each direction during a complete rotation of the shaft 16 and these movements occur while the cutter is at or adjacent to the upper end of each stroke. The cutter bar 20 has a head 21^a mounted to oscillate thereon and carrying an arm 30 rigid therewith and operatively connected to the

upwardly projecting portion of the rod 28. The arm 30 is suitably slotted or formed of telescoping sections so that as the rod 28 is moved back and forth with the slide it will swing the arm 30 and oscillate the cutter bar. The throw of the cam is such in respect to the distance between the plane of movement of the slide and the axis of the cutter bar that the arm 30 is swung through approximately 90°, as illustrated particularly in Fig. 5. The arm is shown as made of two sections one integral with the head 21^a and the other 30^a telescoping thereon and slidable on the rod 28.

For supporting the material against the action of the cutter and for advancing the material, I provide a supporting and feeding wheel 31 mounted on the shaft 16 and with its upper edge substantially flush or slightly above the plane of the table or other support over which the material passes. This wheel may be formed of two similar sections 32 and 33 secured to a sleeve 34 and having peripheral wall portions spaced apart to leave a zigzag slot 35 slightly wider than the thickness of the knife and with each straight portion of the slot of a length substantially equal to the width of the knife. Along each edge of the slot and preferably along the opposite edges of the peripheral face of the wheel are series of projections 36 which hold the slide away from the main surface of the wheel but effectively support it and prevent the hair on the under side of the hide from being clamped and held between the hide and the peripheral wall of the wheel. Thus the hairs may swing away from the hide and will not be cut during the downstroke of the knife into the registering slot on the wheel. Means are provided for rotating the wheel intermittently so as to feed the material forward when the cutter is in raised position, such feeding mechanism operating at all times to maintain the wheel in proper registry so that the cutter in descending will enter the slot of the wheel. With the entire cutter at one side of the axis of the cutter bar and with this axis in the plane of each alternate angle of the slot, it is necessary to rotate the wheel through such angular distance as will advance the slot one complete notch during each alternate downstroke or cutting stroke of the cutter. For instance, with the axis of the cutter bar above the point *a* in Fig. 5, the cutter bar would descend once in the slot portion *b*, ascend, rotate through 90°, descend through the slot portion *c* and then ascend. Before the next descent of the cutter, the wheel would be rotated to the position shown in Fig. 5. If the cutter extended to equal distances upon opposite sides of the axis of the cutter bar and said axis was in the medial plane of the wheel, then it would be neces-

sary to advance the wheel a distance equal to one half the width of each notch or serration between each two successive cutting strokes. Various means may be provided 5 for effecting this intermittent rotation of the supporting and feeding wheel 31. As shown, the wheel has a ratchet wheel 38 rigidly secured thereto and the wheel supporting sleeve 34 is mounted on but unsecured to the shaft 16. The frame 25 of the slide carries a pawl 42 engaging with the ratchet wheel 38 to rotate the latter when the slide moves in one direction and to freely pass over the teeth when the slide moves 10 in the opposite direction. As the shaft 16 rotates at only one half the speed of the shaft 13 this will advance the wheel 31 once for each two cutting strokes of the blade. The cam thus has a feeding movement 15 through the pawl only while the cutter is at the upper end of every alternate down-stroke. Suitable means may be employed if desired for holding the wheel stationary during return movement of the pawl and 20 for limiting each forward feeding movement. With the material advanced for each successive cutting stroke as above suggested, a separate cam would be provided of such shape as to give two separate feed movements to the pawl 42 with intervals there- 25 between during each complete rotation of the shaft 16.

For maintaining the material in proper engagement with the upper exposed peripheral portion of the feed wheel 31 I provide a suitable pressure foot. This is illustrated in the form of a pair of rollers 45 mounted on horizontal axes, one in advance of the cutter and the other beyond it. These 30 rollers are mounted in suitable yokes 46 carried by a pressure foot bar 47 slidable in the head 12^a. The rollers may be held down solely by gravity, but preferably by a spring, such for instance as a coil spring 48 35 on the pressure foot bar. These rollers hold the material against projections on the peripheral surface of the wheel and as they are smooth and free to rotate about their axes, they insure the advancement of the 40 material with the wheel during the rotation of the latter.

For removing any hair or fragments which might adhere to the periphery of the wheel or the teeth or projections I preferably 50 provide a brush 50. This may be of any suitable character but is illustrated as a rotary one driven from the shaft 16 by a belt 51. Particles that fall into the interior of the wheel from the cutter may fall out or 55 be brushed out at the lower side of the wheel. The end walls of the wheel may be made of skeleton form as shown in Fig. 8 to reduce weight and facilitate cleaning of the interior.

60 My improved machine may be operated

from any suitable source of power and the frame may be so designed that the operator sits in front of it and draws the material through or feeds it through away from him as in the ordinary sewing machine, or the operator may sit at the end of the machine so as to better hold the material both in advance of and behind the part being cut. The material may be guided through the machine so as to form a straight or curved row of 70 serrations. It is not necessary to mark any of these serrations on the material but only to mark or indicate the line of one series of apexes thereof. It is thought that the operation of the machine will be clearly apparent from the foregoing description, and that the principles of the machine will be 75 fully understood from the description of this one specific embodiment thereof.

It will be evident that I might have a pair 80 of the reciprocatory cutter bars and cutters connected together for simultaneous reciprocation and oscillation and spaced apart a distance equal to the width of a serration so that two cuts would be made by each down-stroke and two complete serrations cut by each pair of strokes. In this case, it is evident that the wheel should be rotated a distance equal to two serrations after each pair 85 of cutting strokes. It will also be evident that instead of a flat knife of the character shown in Fig. 7, a V-shaped knife might be employed for simultaneously cutting the two 90 sides of the serrations. In this case, the oscillating mechanism might be avoided and the wheel would be rotated a distance equal to the width of the complete serration after 95 every cutting stroke. Various other changes and modifications may be made as will be evident to those skilled in the art.

Having thus described my invention what I claim as new and desire to secure by Letters Patent is:

1. A machine of the class described, including a wheel having a zigzag slot in the 110 periphery thereof, a reciprocatory knife, means for reciprocating the knife and rotating the wheel whereby the knife enters the successive sections of the zigzag slot in succession.

2. A machine of the class described, including a wheel having a zigzag slot in the 115 periphery thereof, a reciprocatory knife, means for reciprocating the knife and rotating the wheel whereby the knife enters the successive sections of the zigzag slot in 120 succession, and means for maintaining a sheet of material in engagement with the periphery of the wheel during the rotation of the latter, whereby a zigzag cut is made in the 125 material corresponding to the slot in the wheel.

3. A machine of the class described, including a wheel having a zigzag slot in the 130 periphery thereof, means for intermittently

rotating said wheel, and a reciprocatory knife timed to enter the successive straight sections of said slot.

4. A machine of the class described, including a wheel having a zigzag slot in the periphery thereof, means for intermittently rotating said wheel through an angular distance corresponding to the distance between successive points of said slot, and a knife 10 mounted to enter the successive portions of the slot between successive rotary movements of the wheel.

5. In a machine of the class described, having a reciprocatory cutter, a wheel having its periphery formed to receive said cutter, a pair of rollers for holding sheet material against a portion of the periphery of the wheel, and means for advancing the wheel.

20 6. In a machine of the class described, having a reciprocatory cutter, a wheel having its periphery formed to receive said cutter, a pair of rollers for holding sheet material against a portion of the periphery of 25 the wheel, and means for advancing the wheel, said wheel having a series of projections for engagement with the material to insure its advancement with the wheel during the rotation of the latter.

30 7. A machine of the class described, having a rotary work advancing and supporting wheel, provided with a zigzag knife receiving slot in the periphery thereof, and projections at opposite sides of the slot for 35 supporting sheet material out of engagement with the peripheral surface of the wheel and preventing the clamping of nap or hair on the material against the body of the wheel.

8. A machine for forming a continuous 40 zig-zag cut in sheet material including a reciprocatory oscillatory cutter, and means for feeding a sheet of material there beneath to such distances between successive cutting strokes that each cut at its ends will meet 45 the ends of adjacent cuts at an angle to form a series of serrations along the edge of the sheet.

9. A machine for forming a series of serrations on a sheet of material, including a 50 cutter of materially less width than the sheet and equaling the width of one side of the desired serration, means for reciprocating said cutter, means for oscillating said cutter between successive cutting strokes, and 55 means for intermittently advancing the material between cutting strokes to such a distance that successive cuts meet at their ends at the angles of a zigzag line.

10. A machine for forming serrations on 60 a sheet of material, including a reciprocatory cutter, means for turning said cutter about an axis parallel to the direction of the cutting stroke and intersecting one end of the cutting edge, said turning movement being 65 effected between successive cutting

strokes so as to make a V cut, and means for advancing the material after each two successive cuts to a distance equal to the distance between the extremities of said V cut to form a continuous zigzag line.

70 11. A machine for forming serrations on a sheet of material, including a reciprocatory knife, means for turning the knife before every cutting stroke and about an axis intersecting the cutting edge at right angles to the plane of the material, and means for advancing the material between cutting strokes to such a distance that successive cuts made before and after advancement intersect at an angle.

75 12. A machine for forming serrations on a sheet of material, including a reciprocatory cutter, means for turning said cutter through approximately 90° after a cutting stroke so that two successive cutting strokes 80 make a right angle V cut, and means for advancing the material after each two successive cuts to a distance equal to the distance between the extremities of a V cut.

85 13. A machine for cutting a zig-zag line, 90 including a reciprocatory cutter, means for turning it about an axis intersecting its cutting edge and substantially at right angles to the plane of the material to be cut, and means for intermittently advancing the material, the extent of each advancement being equal to the projection of the cut in the plane of the material and in a direction at right angles to the path of movement of the material whereby cuts made before and after 100 advancement intersect to form a continuous zigzag line.

95 14. A machine of the class described, including a work support, a reciprocatory cutter bar, a pair of parallel shafts geared together, one being disposed above the support and the other below, means operated from the upper shaft for reciprocating the cutter bar, and means operated from the lower shaft for turning the cutter about an axis 110 parallel to the direction of a cutting stroke.

105 15. A machine of the class described, including a work support, work feeding means carried thereby and presenting a zigzag slot, and a reciprocatory oscillatory cutter adapted to enter the successive sections of said slot 115 as the latter advances with the work.

120 16. A machine of the class described, including a work feeding member having a zigzag slot, a reciprocatory knife, means for advancing said feeding member beneath said knife, and means for turning said knife between successive reciprocations whereby it enters the successive sections of said slot and cuts a zigzag line in the material advanced 125 by said feeding member.

Signed at New York, in the county of New York and State of New York, this 18th day of July, A. D. 1918.

MARTIN ZAWISTOWSKI,
